FRAME AND CONNECTING PARTS FOR
TETRAHEDRAL KITES

Leo J. Fishel, New York, N. Y.

Application August 11, 1932. Serial No. 628,319

10 Claims. (Cl. 244—22)

This invention relates to aerial vehicles, the invention being more particularly related to tetrahedral kites.

It is well known in the art to produce kite structures in the form of a skeleton of a tetrahedron. It is also known to produce a tetrahedral kite structure which is multicellular in character; that is to say, which is composed of a number of cells, each of which is in the form of a tetrahedral frame. The various tetrahedral frames making up the structure may be connected at adjacent corners in such manner that the composite structure will itself have the form or outline of a tetrahedron.

15 My invention has for its object the provision of novel frame parts and corner connectors whereby such tetrahedral kite structures may with ease be quickly and accurately assembled or disassembled, by those interested in the sport 20 of flying kites and particularly by children. Another object is the provision of frame parts and corner connectors which will be light in weight while possessing the qualities of great strength and rigidity.

25 It is within the province of my invention to fashion the frame parts and connectors so that they can be nested in compact arrangement for carriage, packaging, shipment and storage; and further to so fashion these parts that it can be 30 apprehended at a glance just how they are to be put together in building up a kite structure.

With the foregoing and other objects in view, the invention consists in the construction of parts so shaped and fashioned as to combine and 35 cooperate with each other in the performance of the functions and accomplishment of the results hereinafter contemplated, and comprises in its evolution a system for assembling the simple and practical examples and forms illustrated 40 in the accompanying drawing, wherein similar reference characters designate corresponding parts throughout the several views and in which:

Figure 1 is a perspective view of a winged tetrahedral component or cell which may be joined 45 to other similar components in building up a compound tetrahedral kite structure;

Fig. 2 represents a side elevational view, with parts broken away, of one of the six angle strips or webs which enter into the structure of a tetrahedral component;

Fig. 3 is a cross section taken on the line 3—3 of Fig. 2;

Fig. 4 is a cross section taken on the line 4—4 of Fig. 2;

50 Fig. 5 is a side elevational view of an angle

joint device or connector for securing together two tetrahedral components at adjacent corners;

Fig. 6 is a cross section taken on the line 6—6 of Fig. 5;

Fig. 7 is an elevational view, showing two fragmentary tetrahedral components connected at adjacent corners; and

Fig. 8 is a perspective view of an angular reinforcing cover for use on those corners which are not connected to an adjacent tetrahedral component.

Referring now in detail to the accompanying drawing and first to Fig. 1, it will be seen that the four triangular sides or faces of the tetrahedral component *a*, are produced from an assembly of connected frame strips or elongated webs *b*, similar in form and size.

The framing of this tetrahedral cell or component embodies six strips or webs *b* arranged or 75 assembled to produce the four triangular faces and four corners of the tetrahedron.

Each of the parts *b* may be referred to as an angle strip or web, the same comprising two sides 10 and 10' in angular relation. Said sides 80 10 and 10' at the opposite ends thereof, are provided respectively with integral coplanar ears 11 and 12. These ears are triangular in form and correspond in size. The ears 11 and 12 may be referred to respectively as "plain" and 85 "marked" ears, the last-named visibly differing from the first-named in that they are provided with a plurality of circular openings 13 for a purpose that will presently appear.

It is important to note that the ears 11 and 90 12 are provided on the angle strips in alternating relation, so that at one end of the angle strip *b* a plain ear 11 on the side 10' comes opposite a marked ear 12 on the side 10, whereas at the other end of the angle strip a marked ear 12 95 on the side 10' comes opposite a plain ear 11 on the side 10. The sides of each of the angle strips *b* are thus made at their opposite ends with alternating ears having visible differences; although such ears are of the same form and 100 size.

As illustrated in Fig. 1, at each of the four corners *c* of the tetrahedral cell or component, three angle strips *b* converge so that the ears thereof may be united to form a rigid corner. Now, at 105 each corner the three angle strips are assembled in such manner that the plain ears 11 form outside parts, while the marked ears 12 form inside parts. From what has been said it will be understood that each of the angle strips is formed 110

with a plain ear and a marked ear at each end thereof. Therefore, at each corner *c* there are six ears to be brought together so that, at the apex of each triangular face, there will be an assembly of two ears comprising a plain or outside ear 11 and a marked or inside ear 12 which is coextensive with the outside ear and engages with the inside face thereof. The purpose of providing the marked ears 12 in alternating relation with the plain ears 11 is to enable a person who is engaged in assembling a tetrahedral cell or component, to see at a glance by reason of the visible differences between the ears, just how at each corner under assembly the three angle strips may be brought together in order accurately and without mistake to produce the tetrahedral cell. Thus, in assembling a corner, it is only necessary to bring the three angle strips together in such way that a marked ear 12 will always engage the inner face of a plain ear 11. Having thus assembled a corner, the ears at the opposite ends of the angle pieces will be in proper relation for similarly building up the remaining three corners.

25. The triangular ears 11 and 12 are each provided, centrally thereof, with an aperture 14, so that when a corner *c* is assembled a suitable fastening device such as a screw bolt 15 may be passed through each pair of assembled ears 11 and 12. A bolt having thus been passed through the aligned apertures 14 of a pair of ears, a suitable nut 16 may be applied to the bolt for securing the parts together.

30. Two of the four triangular faces of the tetrahedral cell or component may be covered with suitable fabric as 17 in order to provide the wings necessary to give lifting power to the structure. To provide for the application of the fabric, the two sides 10 and 10' of each angle strip are provided with spaced apertures 18 for receiving the sewing thread or lacing 19 which is sewed through the fabric so as to secure the edges of the fabric to the strips, as shown in Fig. 1. A single piece of fabric may be used to cover the

35. two triangular faces, if the central portion of the fabric is passed over one of the angle strips as at 20 so that the free edges of the fabric can be sewed in place to the two strips forming the two remaining sides of the triangle.

40. As is well known in the art, a tetrahedral kite structure having the form or outline of a tetrahedron may be composed of a number of similar winged frames or cells each itself having the form of a tetrahedron. Such a tetrahedral kite structure is sometimes referred to as a multicellular kite, the several similar winged tetrahedral frames or cells being joined at adjacent corners. Now, the angle strips and ears of the present invention have been designed, not only for the

45. purpose of providing easy and ready assembly and to give great strength and rigidity, but also for the purpose of providing corner constructions which will properly combine and cooperate with novel corner connectors whereby firmly and rigidly to connect the tetrahedral cells or components at adjacent corners. My improved corner connectors are also devised for ready and easy application in building up a compound tetrahedral kite structure, as well as for ready and easy

50. removal in disassembling the same.

In the accompanying drawing, 21 denotes my improved corner connector by means of which to connect the adjacent corners of two tetrahedral cells *a* in the manner shown in Fig. 7. Each connector 21 is an angle member, being composed of

two angularly related sides 22 and 22'. Each of the sides 22 and 22' includes two spaced triangular ears 23, the same being of the same size as the ears 11 and 12. Each of the ears 23 is provided, as shown in Fig. 5, with a key-hole shaped slot 24 adapted, when connecting the two adjacent corners, to receive therethrough the screw bolt 15 whereby to be secured in place by the nut 16. The larger portions of the slots 24 are of a size sufficient to admit the passage therethrough of the nuts 16, while the narrowed or restricted portions of said slots are smaller than said nuts. By this arrangement, in connecting two adjacent corners, it is only necessary to loosen the nuts and then apply the connector 21 so that the larger portions of the slots 24 will pass over the nuts; whereupon the connector is pushed up until it fits tightly over the angle, with the restricted portions of the slots 24 receiving therein the screw bolts. When this operation has been effected, the nuts are screwed tightly against the connector, thereby securing the same firmly in place upon the adjacent corners. By means of connectors as 21, I may, for example, connect four tetrahedral cells or components *a* in such manner that the resulting compound structure has itself the form of a tetrahedron. To each free corner of the structure, which is not connected by a connector 21, I may apply an angle corner piece 25, the two angularly related sides 25', 25' of which are each provided with an aperture 26 for receiving the screw bolt 15 whereby to be screwed in place upon the plain ears 11. The sides 25', 25' of each corner piece 25 are, of course, of the same size as the ears 11 and 12. The corner pieces 25 make for symmetrical appearance, and also serve as means for holding the fabric in place.

55. It will be readily evident that the angle strips or webs *b*, being of angular form and of the same size, may be readily nested to make a compact bundle convenient to carry or for storage. The corner connectors may also be nested to make a compact bundle.

60. Owing to the provision of alternating plain and marked ears, it is an easy task to properly assemble each tetrahedral cell, and then by the means of the corner connectors to unite the adjacent corners of the cells so as to produce the compound tetrahedral structure. Children, and even adults, find it both interesting and amusing to assemble and disassemble kite structures composed of my improved frame strips and connectors. A multicellular kite produced from my angle frames and connectors possesses great strength and rigidity and has great lifting power.

65. While I have disclosed and described only one practical embodiment of my invention as reduced to practice, it will be recognized that the disclosure given is an example only, and is susceptible to more or less modification in the form, proportions and relative arrangement of the various parts, and I, therefore, reserve the privilege of resorting to all such legitimate changes therein as may be fairly incorporated within the spirit and scope of the invention as claimed.

I claim:—

70. 1. In a tetrahedral kite frame, the combination of three frame strips which are to be connected to form a corner, each strip being formed for the production of the corner with two thin opposing ears in angular relation, and means for detachably connecting one ear of each strip in lapping relation with an ear of an adjacent strip.

75. 2. In a tetrahedral kite frame, the combina-

- tion of three frame strips which are to be connected to form a corner, each strip being formed for the production of the corner with two thin opposing ears in angular relation, said ears corresponding in size and having correspondingly-positioned apertures therein, and means for detachably connecting one ear of each strip inlapping relation with an ear of an adjacent strip, comprising engaging members adapted to be passed through the apertures of each twolapping ears. 5
3. In a tetrahedral kite frame of the sectional type, the combination of angle strips for outlining the triangular faces of the tetrahedron, means for connecting the angle strips at the corners of the tetrahedron, comprising a triangular ear formed on each end of each side of the angle strips, and means for detachably connecting at each corner an ear of each strip with an ear of an adjacent strip. 10
4. In a tetrahedral kite frame of the sectional type the combination of a plurality of angle strips for outlining the triangular faces of the tetrahedron, means for connecting the angle strips at the corners of the tetrahedron, comprising a triangular ear formed on each end of each of the several angle strips, the alternating end ears of the sides being marked for application, and means for detachably connecting at each corner an ear of each strip with a marked ear of an adjacent strip. 15
5. In a tetrahedral kite frame of the sectional type, the combination at a corner of the frame, of a plurality of angle strips converging at the corner, size-corresponding triangular ears at the corner ends of the angle strips formed on the respective sides thereof, with the ear on one side of each strip overlapping an ear on one side of another strip, and means for detachably connecting each pair of overlapping ears. 20
6. In a tetrahedral kite frame of the sectional type, the combination at a corner of the frame, of a plurality of angle strips converging at the corner, size-corresponding triangular ears at the corner ends of the angle strips, formed on the respective sides thereof, and one being marked for identification, with the ear on one side of each strip overlapping a marked ear on one side of another strip, and means for detachably connecting each ear with the marked ear overlapped thereby. 25
7. In a tetrahedral frame, the combination with a corner composed of a plurality of angular strips the two sides of each of which are formed with size-corresponding ears, providing forlapping the ear of each side over the ear of the side of an adjacent strip, together with a corner connector including angularly related ears corresponding in size with said side ears to embrace a pair of adjacent side ears, all of said ears being provided with apertures, and means adapted to pass through the apertures of each set oflapping ears to afford and maintain an engagement therewith for holding the strips and connector against displacement in any direction. 30
8. As an article of manufacture, a frame strip for tetrahedral kites composed of thin integral angularly related sides of V-shape in cross section, triangular ears formed integral and coplaner with the sides, at opposite ends thereof, and forming at each end of the strip two oppositely disposed ears having the same angle of divergence as said angularly related sides. 35
9. As an article of manufacture, a frame strip for tetrahedral kites composed of thin integral angularly related sides of V-shape in cross section, triangular ears formed integral and coplaner with the sides, at opposite ends thereof, and forming at each end of the strip two oppositely disposed ears having the same angle of divergence as said angularly related sides, all of the ears corresponding in size, and one ear of each of the sides at the opposite ends of the strip being marked to visibly distinguish the same from the two remaining alternate ears. 40
10. As an article of manufacture, a thin frame strip for tetrahedral kites having at one end thereof two integrally connected triangular flat faced ears in angular divergence, a thin connector part including two integrally connected triangular flat faced ears having substantially the same angular divergence to provide for nesting the two pairs of ears in direct flatwise contact and in parallel planes with respect to the length of the strip, and means for connecting together the ears which come in such flatwise contact. 45
